US0D1030857S

(12) United States Design Patent (10) Patent No.: US D1,030,857 S
(45) Date of Patent: * Jun. 11, 2024

(54) MUSIC BOX

(71) Applicant: Fan Xie, Shenzhen (CN)

(72) Inventor: Fan Xie, Shenzhen (CN)

() Term: 15 Years

(21) Appl. No.: 29/907,746

(22) Filed: Jan. 8, 2024

(30) Foreign Application Priority Data

Dec. 22, 2023 (CN) 202330847006.2

(51) LOC (14) Cl. 17-05

(52) U.S. Cl.

USPC D17/24

(58) Field of Classification Search

USPC D17/24, 99; D21/405

CPC G10D 99/00; G10F 1/06

See application file for complete search history.
